UNITED STATES PATENT OFFICE.

RAPHAEL JACOBUCCI, OF PROVIDENCE, RHODE ISLAND, ASSIGNOR OF ONE-HALF TO
GEORGE RIVKIND, OF BOSTON, MASSACHUSETTS.

MULTICOLOR-PRINTING MACHINE.

Application filed November 26, 1921. Serial No. 517,935.

To all whom it may concern:

Be it known that I, RAPHAEL JACOBUCCI, a citizen of the United States, residing at Providence, in the county of Providence and 5 State of Rhode Island, have invented certain new and useful Improvements in Multicolor Printing Machines; and I do hereby declare the following to be a full, clear, and exact description of the invention, such as will enable others skilled in the art to which it 10 pertains to make and use the same.

This invention relates to printing machines and more particularly to multi-color printing machines, the main objects of the 15 present invention being an improvement on Patent No. 1,240,159, granted to me September 11, 1917.

One of the objects of my invention is the provision of a printing machine comprising 20 a rotatable carriage provided with a plurality of sets of rollers and means for causing the rollers to automatically engage the proper inking discs and convey the ink to the proper set of type in accordance with 25 the color whereby each set of type will be inked with the proper color.

A further object of the invention is the provision of means for diverting each carriage supporting form from its circular path 30 and directing it along a straight line at the time it is passing beneath the printing cylinder, such means being utilized to prevent any shock or jar from being conveyed to the type supporting carriage so that the proper 35 printing will be carried out.

A further object of the invention is the provision of means for operating additional inking discs and for dividing the ink fountain whereby several colors may be used in 40 the printing, the means for operating the discs being utilized to operate a single disc or a pair of discs.

With the above and other objects in view, the invention consists in the novel features 45 of construction, combination and arrangement of parts hereinafter more fully set forth, pointed out in the claims and shown in the accompanying drawings, in which:

Figure 1 is a plan view of the press with 50 parts thereof broken away to illustrate details of construction;

Fig. 2 is a vertical transverse sectional view on the line 2—2 of Fig. 1;

Fig. 3 is a horizontal view taken on the 55 line 3—3 of Fig. 2;

Fig. 4 is a detail transverse sectional view illustrating means for supporting two inking discs, and

Fig. 5 is a fragmentary detail showing the 60 inking plate and fountain actuating mechanism.

Referring now more particularly to the drawings, the numeral 1 indicates a supporting member formed of a plurality of radially projecting supports and mounted upon the upper end of the member 1 is a base 2 which is bolted or otherwise secured to the supporting member 1 as illustrated in Fig. 2. At the center of the supporting member 1, is a recessed portion 3 and extending upwardly from the base 2 is a bearing sleeve 4 which communicates directly with the recess 3 and in which is mounted the central supporting standard or hub 5 of a rotary table 6. Keyed to the lower end of the 70 standard 5 is a bevel gear 7 arranged within the recess 3 and cooperating with a gear 8 upon the inner end of the operating shaft 9; said shaft being suitably mounted in bearings 10 and having fast and loose pulleys at 75 its outer end so that it may be rotated from any suitable source. From the hub 5 radiates a plurality of spokes 11 carrying at their outer ends the table 6 shown in the drawings as of skeleton formation and made 80 up of two rings whereof the outermost travels on the supporting casters or wheels 12 which tend to support the outer edge of the table 6 in spaced relation with the base 2.

In order to accommodate various colors 85 of ink, I have shown in Fig. 1 wherein a single inking disc may be replaced by two discs. Each of the single discs 13 is rotatably mounted on a pin 14 and carries on its under side teeth 15 as usual and adjacent each 90 disc is a fountain 16. The usual mechanism 17 may be used for intermittently rotating the disc and causing the feed of the fountain, and this mechanism is actuated by a lever 18 tripped by a cam 19 or a series of 95 cams located preferably in advance of the cylinder as shown. As illustrated in Fig. 1 I have provided tripping means for a single disc and also for double discs.

In Fig. 4 I have illustrated the manner of 100 supporting two discs in the place of a single disc, said support comprising a standard 20 having radiating arms extending in opposite directions and provided with upwardly projecting pins 21 upon which the discs 22 110

are mounted. I have also illustrated means in the form of a partition 23 whereby the ink fountain 16 may be divided to form two separate chambers for the reception of two different colored inks to correspond with the spaced discs arranged adjacent the fountain. From the illustration in Fig. 1, it will be apparent that three or more colors may be utilized in printing by changing any of the single discs 13 to the double discs 22 and placing the partition 23 within the ink fountain 16.

For the purpose of illustration I will describe the device as using three colors although it will be apparent from the above that various colors may be utilized by changing the discs and partitioning the fountains. In the drawings, I have illustrated three chases or type carriages, one with red, another with green and the third one with blue. For each disc or set of discs I prefer to use a set of three rollers generally indicated as at 24, each set of rollers being raised and lowered by suitable mechanism to apply ink to the proper chase at the proper time. Extending upwardly through the hub 5 is a pillar 25 and secured to the head of this pillar at the upper end thereof is a spider 26 carrying in the present case, three arms 27 each having, at its outer end, an upright plate 28 provided with a series of slots 29 and rising rigidly from the base 2 is a similar plate 30 having an equal number of upright slots 31, in said slots rest the trunnions 32 of the rollers 24 and each roller has on its trunnions wheels 33 spaced according to the gage of the rails upon which they run. Surrounding the central portion of the table 6 is an annular track-way having opposed depressions formed therein to receive the wheels 33 upon the inner ends of the set of rollers which are used to apply the ink to the chases indicated as printing the blue impressions upon the material. The depressions formed in the annular track-way are generally indicated by the numeral 34. An intermediate set of depressions as at 35 are formed in the track-way and are used for applying green ink to the proper chase. A third set of depressions is indicated at 36, said depressions being used for causing the rollers 24 which are applying the red ink to the proper chase to move over the disc previously supplied with the ink and also causing the rollers to contact with the proper chase when it reaches that point beneath the rollers.

An annular track-way is also formed upon the outer edge of the table 6 and is provided with depressions corresponding with the depressions formed upon the inner annular track-way whereby the wheels which support the rollers upon both ends will be dropped downwardly into the proper depressions at the proper time. As illus-

trated, the depressions 37 are formed opposite the depressions 34 so that when the rollers which are operating upon the blue ink, reach the position shown in Fig. 1, the wheels thereof will move within the depressions 34 and 37, dropping the rollers downwardly so that they will engage with the disc 13 and obtain ink therefrom. Therefore, when the chase which contains the type for printing the blue impression reaches the point where the rollers are now located, through the rotation of the table 6, the rollers will be again lowered through the medium of the depressions 34 and 37 formed upon the opposite side of the chase so that the ink will be applied to the type in the chase. Intermediate depressions 38 are formed in the outer annular track-way and arranged in opposed relation with the depressions 35 so that the rollers which apply the green ink to the proper chase will be raised and lowered at the proper time. Outer depressions 39 are formed in the outer annular track-way and arranged in opposed relation with the depressions 36 which cooperate to raise and lower the rollers that apply the red ink to the proper chase. Mounted upon the table 6 and arranged within the inner annular track-way is a gear ring 40 which cooperates with a bevel gear 41 mounted upon the shaft 42, said shaft being journalled within suitable bearings 43 and mounted upon the shaft is a cylinder 44 beneath which the type chases pass for carrying out the printing operation, thus as the table 6 is rotated through the power applied to the shaft 9, the cylinder 44 is caused to rotate through the gear ring 40 and gear 41.

Formed upon the base member 2 intermediate the center and the outer edge are the spaced track rails 45 upon which the trucks 46 ride, the wheels of said trucks being arranged for movement upon the track rails 45. These trucks 46 which carry the type chases are loosely connected to the table 6 through the medium of pins 47 extending upwardly through suitable slots 48 formed in the top of the table 6, said slots permitting a free movement of the pins 47 to compensate for the movement of the trucks during their passage over the rails 45 around the base 2. It will be noted that upon rotation of the table 6, the trucks which carry the type chases will be moved around upon the rails 45, but in order to cause the trucks to assume a straight away position while they are passing beneath the cylinder 44, the rails 45 are arranged in spaced parallel relation extending from a point to one side of the cylinder support to the other side, these straight away or parallel portions being generally indicated as at 49, and it will be apparent from this that when the forward wheels of the chase supporting trucks en-

gage with these parallel portions, they will be caused to run in a straight line, as well as the rear wheels, causing the truck to pass beneath the cylinder in a straight away position wherein the cylinder and the type chase, when in contacting position will be arranged in parallel relation during the printing operation. It will be noted that by arranging the parallel portions 49 of the track rails 45 beneath the cylinder 44, the trucks will be readily caused to assume a straight away position while passing beneath the cylinder 44, but will readily accommodate themselves to the circular track-way after having passed beneath the cylinder, the movement of the pins 47 in the slots 48 permitting a free movement of the trucks when entering the straight away portion on passing therefrom.

20 By providing trucks such as illustrated in the accompanying drawings and forming a straight away portion in the track-way, beneath the printing cylinder, all guide arms and the like are eliminated.

25 In the operation of printing various colors with my improved machine, we will assume that the machine is to print three forms in red, green and blue, respectively, it being understood that the double discs shown in Fig. 1 will be replaced by a single disc 13. The chases containing the forms are mounted upon their respective trucks, the red being upon the forward truck in accordance with the direction in which the table is traveling, the green upon the second truck and the blue upon the third truck, the proper colors are then placed within the fountains 16 and as the table rotates, the rollers through the several depressions in the inner and outer track-ways, will be lowered at the proper time to obtain ink from the proper discs. As illustrated in Fig. 1, all of the rollers are in position for contact with the discs 13 being supplied with the proper amount of ink and the proper color. As the chase containing the type for the red printing reaches the furthermost set of rollers, the depressions 36 and 39 will cause the rollers to move downwardly for engagement with the type in the chase, applying the red ink thereto, this same operation is carried out with the chase containing the type for the green and blue ink, said type receiving its proper amount of ink from the respective rollers. Upon return of the chase containing the type 55 for the red printing, the trucks will pass beneath the cylinder 44, the straight away portions 49 of the truck causing the chases to be moved in their proper relative positions beneath the cylinder 44, whereby the 60 ink which has been applied to the type within the chases will be transferred to the card or other material carried by the cylinder.

As set forth in the description above and illustrated in the accompanying drawings, 65 the single discs 13 may be replaced by the double discs 22, this being carried out by having the supporting arms 21 arranged within the bearing provided for the supporting pins 14 of the discs 13. The fountains also can be divided equally by inserting the partition 23 should it be desired to print more than three colors.

I claim:

1. In a device of the character described 75 having a fixed base, a rotary table and a cylinder, a circular track-way on the base having spaced parallel portions extending beneath the cylinder and a bed plate carriage supported by a truck operating on said 80 track-way.
2. In a device of the character described 85 having a fixed base, a rotary table and a cylinder, a circular track-way on the base having spaced parallel portions constituting a straightaway section extending beneath the cylinder and a bed plate carriage comprising a body slidable radially relative the rotary table and adapted to be engaged and operated thereby and a truck part pivotally 90 connected to said body said truck having traction wheels engaging the track-way to positively support and guide the bed plate therefrom substantially as specified.
3. In a device of the character described 95 the combination of a fixed base, a rotary table, a cylinder supported from the base over the table, a bed plate, means for supporting the bed plate directly from the base comprising a truck having traction wheels 100 and guiding means for the bed plate comprising tracks carried by the base.

In testimony whereof I affix my signature.

RAPHAEL JACOBUCCI.
